UNITED STATES PATENT OFFICE.

JAMES CRUICKSHANK HENDERSON MACBETH, OF LONDON, AND ALFRED JAMES JUNG, OF WESTMINSTER, LONDON, ENGLAND, ASSIGNEES TO THE WIRELESS PRESS, LIMITED, OF LONDON, ENGLAND.

CODES, CIPHERS, AND THE LIKE.

1,195,701.

Specification of Letters Patent. Patented Aug. 22, 1916.

Application filed April 6, 1916. Serial No. 89,456.

To all whom it may concern:

Be it known that we, JAMES CRUICKSHANK HENDERSON MACBETH and ALFRED JAMES JUNG, both subjects of the King of Great Britain, residing, respectively, at 11 Long Acre, London, England, and at 7^a Princes street, Westminster, London, England, have invented new and useful Improvements in or Relating to Codes, Ciphers, and the like, of which the following is a specification.

This invention relates to telegraphic or other signal codes, ciphers or the like and has for its object to provide a ready means for coding or decoding a message by which the code may be easily changed and which can be kept safe against unauthorized access.

We employ a stationary table or plate bearing figures (or it may be letters) arranged in rows and columns and on two adjacent sides thereof we mount two rotatable cylinders or prisms each bearing a number of series of letters (or it may be figures), each series being furnished at one end with a determining or "key" figure or letter. Each prism is connected to a lock, such as a Yale lock for instance, so that it can only be turned by the insertion of a key and the whole is inclosed in a box secured by a suitable lock. Preferably a counter is so mounted in the box that it registers the number of times the box is opened. Preferably also the prisms and their locks are so arranged that in the only position in which the keys can be inserted and withdrawn, no letters (or figures) are visible on the prisms.

The invention is illustrated in the accompanying drawings, Figure 1 of which shows a code box open and ready for use; Fig. 2 is an underside view showing the prisms; Fig. 3 is a cross section on the line A—A of Fig. 1; Fig. 4 shows a detail; Figs. 5 and 6 are horizontal sections through the axis of one of the prisms showing a modification and Figs. 7 and 8 are vertical transverse sections thereof.

1 is a box which is secured by a lock 2 and in which is secured a plate 3 engraved with numerals arranged in five rows and twenty columns.

4 is a prism mounted in bearings so that it can be rotated by the insertion and rotation of a key 5 in a barrel lock 6, the barrel of which is connected to the prism. The 55 prism carries nine series of letters, which are all consonants, numbered 1 to 9; of these No. 1 is seen. One face of the prism or a portion thereof is left blank and the prism is so arranged with regard to the lock that 60 the key can only be withdrawn from the lock when the blank face is visible.

7 is a second prism similar to the prism 4 and having the vowels upon it. A ratchet and pawl 8 prevent the backward rotation 65 of each prism.

9 is a counter actuated by a pin 10 on the lid of the box each time the lid is closed.

While we have called the parts 4 and 7 prisms, it will be understood that they may 70 be cylinders or in fact any adjustable devices suitable to carry characters in the manner specified.

The locks employed for the prisms or character-carriers may be of any suitable 75 construction. Many such locks are commonly known. It is important that locks should be employed of the kind in which the keys can be inserted and withdrawn only when the keys are in a given position so 80 that they cannot be inserted or withdrawn when the character-carriers are in position for use. Where two character-carriers are employed, as above specified, each controlled by a key, the keys may be of different kinds 85 one of which may be held by one person and the other by another so that it will not be possible to adjust the apparatus for use unless the two persons holding the keys are present and perform the necessary opera- 90 tions.

The counting mechanism 9 which is operated by the pin 10 may be of any suitable kind. Many such devices are commonly used for indicating the number of times a 95 box or drawer is opened or closed.

When it is desired to translate a message into cipher, the two prisms 4 and 7 are first set so that the numbers at the beginning of the series of letters are those corresponding to the "key" number (in the case illustrated this number is 11) and then any two digits

can be translated into a pronounceable syllable (e. g. 48=il, 76=ov) or vice versa.

With two prisms having each nine series of letters there are eighty-one different 5 "key" numbers and the "key" can be changed whenever it is thought desirable or should there be any suspicion that the cipher in use has been ascertained by an unauthorized person.

- 10 To give greater security we may make the "key" numbers adjustable with regard to the series of letters as shown in Figs. 5 to 8. Here the prism 4, for instance, is not made in one with the piece 11 which carries 15 the "key" numbers but is connected to it by a pin 12 which can enter any one of eight holes 121, the prism in this case having eight faces. The piece 11 is normally held close up to the prism by a spring 13 but 20 when it is desired to change the "key" numbers relatively to the series of letters, a key 14 is inserted into a lock 15 depressing a spring plunger 16 which normally engages one end of a lever 17 the other end of which 25 engages the piece 11. The key, on being turned, turns the lever 17 and thus withdraws the piece 11 from engagement with the pin 12 so that the piece can be rotated to change the "key" numbers. If desired 30 the prism may be made in more than one piece so that the series themselves can be varied. It will be understood that the communicating parties prearrange which series of letters or characters on the two prisms 35 are to be used and each party before communication is established properly sets the prisms so that the key numbers correspond, for instance in the drawings the key number shown on each prism is 1 which combined give the number 11 as the key. Many 40 code books have in addition to an arbitrary word, to express a phrase or phrases, a series of numbers which may be telegraphed in substitution for this arbitrary code word.
- 45 To avoid the expense and difficulty of calling numbers and also to insure a greater element of secrecy frequent use is made of some system of transforming the ciphers or numbers into pronounceable words. Assuming that it is desired to telegraph the 50 numbers 103486 and 259766 the sender of the message in using our apparatus will set the prisms according to the key number agreed upon, for instance 11, as shown in 55 the drawings. The sender of the message when transmitting the number 103486 first locates the number 10 on the number plate and then writes down the letter at the top of the vertical column of numbers in which 60 10 stands, and then the letter at the left on the horizontal column in which it lies, or he writes them in the reverse order. Reading the letter at the top first and then the one at the left gives the syllable "na." In

like manner the other numbers are found 65 and the syllables written until the word "naseju" is found and in like manner by finding the numbers 259766 the word "hewujo" is found. These words are then sent and the receiving party after having set his instrument in accordance with the key agreed upon would find the numbers in the number plate corresponding with the syllables received and he would then be able to translate these syllables into numbers until finally the 75 numbers are obtained which correspond with the words, phrases or sentences to be obtained. In other words, having received the syllables he can find the numbers and then by referring to a code he can find the 80 meaning of the numbers.

What we claim is:—

1. In means for translating into and from cipher, the combination of a table bearing rows and columns of characters, two movable carriers each of which bears a plurality of series of characters having designating key-characters thereon, one of which carriers is arranged parallel to the rows and the other to the columns, and means for adjusting the character-carriers. 90

2. In means for translating into and from cipher, the combination of a table bearing rows and columns of characters, two rotatable carriers each of which bears a plurality of series of characters having designating key-characters thereon, one of which carriers is arranged parallel to the rows and the other to the columns, and means for rotating the character-carriers. 95

3. In means for translating into and from cipher, the combination of a table bearing rows and columns of characters, two movable carriers each of which bears a plurality of series of characters, one of which carriers is arranged parallel to the rows and the other to the columns, means for adjusting the carriers, and independently operated devices for locking each of said carriers. 105

4. In means for translating into and from cipher, the combination of a table bearing rows and columns of characters, two rotatable carriers each of which bears a plurality of series of characters, one of which carriers is arranged parallel to the rows and the other to the columns, and separate key-operated devices for locking each of said carriers. 115

5. In means for translating into and from cipher, the combination of a table bearing 120 rows and columns of characters, two movable carriers each of which bears a plurality of series of characters and a key-character for each series, one carrier arranged parallel to the rows and the other to the columns, means for adjusting the key-characters independently of the series of characters, and means for adjusting said carriers. 125

6. In means for translating into and from cipher, the combination of a table bearing rows and columns of characters, two rotatable carriers each of which bears a plurality to the columns, means for rotating the key-
5 of series of characters and a key-character characters independently of the series of characters, and means for rotating said carriers. 10
for each series, one of said carriers being
arranged parallel to the rows and the other
JAMES CRUICKSHANK HENDERSON MACBETH.
ALFRED JAMES JUNG.
